UNITED STATES PATENT OFFICE.

EGBERT HAMILTON, OF MINNEAPOLIS, MINNESOTA.

DESIGN FOR A LAMP SHADE.

Application filed November 18, 1922. Serial No. 4,329. Term of patent 3½ years.

To all whom it may concern:

Be it known that I, EGBERT HAMILTON, a subject of the King of Great Britain, residing at Minneapolis, in the county of Hennepin and State of Minnesota, have invented a new, original, and ornamental Design for Lamp Shade, of which the following is a specification, reference being had to the accompanying drawing, forming part thereof.

In the drawings:

Fig. 1 is a view in side elevation of the lamp shade shown in the design; and

Fig. 2 is a top plan view of the lamp shade.

I claim:—

The ornamental design for a lamp shade, as shown.

EGBERT HAMILTON.
